UNITED STATES PATENT OFFICE.

EMRICH W. VALKO, OF CLEVELAND, OHIO, ASSIGNOR TO FIRST CATHOLIC SLOVAK UNION OF THE UNITED STATES OF AMERICA, OF CLEVELAND, OHIO, A CORPORATION OF OHIO.

DESIGN FOR A BADGE.

Application filed December 16, 1925. Serial No. 15,771. Term of patent 14 years.

To all whom it may concern:

Be it known that I, EMRICH W. VALKO, a citizen of the United States of America, residing at Cleveland, county of Cuyahoga, and State of Ohio, have invented a new, original, and ornamental Design for Badge, of which the following is a specification, reference being had to the accompanying drawing, forming part thereof.

In the drawings:

I claim:

The ornamental design for a badge, as shown.

EMRICH W. VALKO.
